UNITED STATES PATENT OFFICE.

DALE M. BOOTHMAN, OF PARNASSUS, PENNSYLVANIA, ASSIGNOR TO ALUMINUM SEAL COMPANY, OF PITTSBURGH, PENNSYLVANIA, A CORPORATION OF PENNSYLVANIA.

CLOSURE SEAL.

Application filed October 11, 1922. Serial No. 593,791.

To all whom it may concern:

Be it known that I, DALE M. BOOTHMAN, a citizen of the United States, and a resident of Parnassus, in the county of Westmoreland and State of Pennsylvania, have invented a new and useful Improvement in Closure Seals, of which the following is a specification.

The invention relates to closures or sealing devices for hermetically sealing the mouths of containers in which food and like products are packed. While the invention is broadly applicable to a wide variety of containers, it is particularly useful in connection with the sealing of glass tumblers such as are ordinarily used for packing jellies, peanut butter and other articles having similar characteristics and requirements as far as concerns their packing.

Usually the seals for glass tumblers and like containers require a special finish or projecting bead at the top of the tumblers for holding the seal. This finish is objectionable, among other reasons because it renders the tumblers unsuitable for use on the table as drinking glasses. The special top finish plainly indicates that the tumblers originally were jelly glasses or the like, and makes them unsightly for table use, although their cost is a considerable proportion of that of the entire package, and although in general shape they are well suited for table use. Furthermore, the usual seals for such containers occasionally fail when subjected to interior pressure, as for example the pressure incident to the sterilizing of food packed in the containers. Also, the usual seals are often difficult to open or break, frequently requiring the use of household or special implements or tools.

An object of this invention is to provide a hermetic closure or seal which may be economically manufactured and applied and which can be easily and certainly opened without the use of any tool, and the cap of which, after the seal is broken, may be satisfactorily used for a temporary cover for the container while the contents are being consumed.

Another object is to produce a side-seal or closure adapted for use on glasses, tumblers

and similar wide-mouthed receptacles, which will withstand a high internal pressure during the process of sterilization of the container, and thus avoid the breaking of the seals or the blowing off of the caps during sterilization.

Another object is to provide sealing means whereby tumblers having the form and pattern of drinking glasses may be used for packing jellies and other food products without the necessity of providing such tumblers with a special finish or projecting bead at the top for holding the seal.

The invention is illustrated in the accompanying drawings of which Fig. 1 is a combined side and vertical central sectional view of a glass tumbler provided with a simple form of seal embodying the invention; Fig. 2 a view similar to Fig. 1 showing additional features of the invention in the preferred embodiment thereof; Figs. 3 and 4 views similar to Fig. 1 showing different applications of the invention; and Fig. 5 a central sectional view of a closure before it is applied to a container.

In the practice of the invention an annular space is formed between the outer wall of the open top of a container and the inner wall of a depending substantially cylindrical skirt of a closure or cap, and in such space there is placed a sealing gasket of flexible compressible material which is held in sealing position by a relatively soft and bendable metal wire pressed firmly against the exposed edge of the gasket, the wire in turn being held in place by its engagement between the container and cap skirt and serving also to hold the cap upon the container.

Some of the features of the invention are illustrated in Fig. 1 which shows the applicability of one embodiment to seals for wide-mouthed containers such as jelly glasses, tumblers and the like, and with reference to which the structural features of the invention and the manner of practicing it may be explained. A tumbler 1 is covered by a cap 2, which, before being applied to the tumbler, has a substantially cylindrical depending skirt 3, as shown in Fig. 5, and the cap is sealed to the mouth of the tumbler by a gasket 4 and retaining wire 5.

Preferably the annular space mentioned above for receiving the gasket and retaining wire is wedge-shaped in cross section. This shape may, and preferably does, result from the usual taper or slope of the outer wall of the tumbler by reason of its diameter at its base being somewhat smaller than at its top. While in the practice of the invention the slope of the tumbler may vary, I have found that a suitable and convenient slope to produce a sufficiently wedge-shaped annular space is from four to six degrees.

In forming the seal the cap 2 is first applied to the top of the tumbler, and the gasket 4, which in the embodiment of the invention shown in Fig. 1 is a continuous ring, is then forced upwardly into the narrower portion of the space between the tumbler and cap skirt 3. Against the exposed lower face of the gasket the retaining wire 5 is then firmly pressed, making at least a complete revolution around the tumbler. The retaining wire is preferably of such diameter as to slightly expand outwardly the skirt 3 of the cap so that the resiliency of the skirt acting inwardly upon the wire causes the wire to firmly grip the container, and the wire, thus gripping both the container and the cap, effectively holds the cap upon the container. Furthermore, the outwardly expanded skirt continuously presses yieldingly inwardly upon the gasket to press it into sealing position.

It has been found that by forcing one complete turn of the retaining wire against the gasket there is formed a tight and durable seal of such a character that pressure on the inside of the cap tending to remove it from the container results in more firmly compressing the sealing gasket and hence further tightening the seal. This has been found to be the case regardless of whether or not the lower end of the skirt is turned inwardly. However, to prevent dust and dirt from finding lodgment in the seal, and also to stiffen the skirt, to avoid rough edges, and to assist in holding the retaining wire against being accidentally removed during handling and shipping of the container, the lower edge of the skirt is preferably crimped inwardly as illustrated in full lines in the drawing. To facilitate the opening of the container, the end 6 of the retaining wire is preferably bent downwardly so that its outer end protrudes below the lower edge of the skirt sufficiently to be engaged for the purpose of opening the container.

To open a container sealed with this closure, the protruding end 6 of the retaining wire 5 is grasped and pulled downwardly until it is entirely removed. As the wire unwinds from about the container it straightens to a considerable extent the inwardly crimped portion of the skirt 3 of the cap, and when the wire has been entirely re-

moved the cap is held in position only by such vacuum as there may be in the container and by the friction between the gasket 4 and the walls of the container and cap skirt. By perforating the top of the cap so as to destroy the vacuum, or by removing the gasket by any convenient means such as a knife blade, fork tine, or other household implement, or, in some cases by simply grasping the container and cap and revolving them with relation to each other, the cap may be easily removed from the container.

As previously indicated, the invention contemplates the provision of a seal requiring no special tool or other implement for opening it, as is sometimes necessary for the particular form of seal just explained. To such end the closure is preferably of the form illustrated in Fig. 2. Instead of using a continuous sealing ring, the gasket is a string or cord-like member 4^a, which, when placed in the annular space between the container 1^a and the skirt 3^a of a cap 2^a, laps upon itself, and the retaining wire is arranged with relation to the lapped ends of the gasket to facilitate the removal of the gasket. When, in forming the seal, the string-like gasket 4^a overlaps its inner end 7, the inner end 8 of the retaining wire 5^a is introduced between the overlapping portion of the gasket and is wound completely around the container and against the gasket so that the general arrangement of the gasket and retaining wire is as indicated in the drawing. The retaining wire has its outer end protruding below the lower edge of the cap skirt in the manner and for the purposes explained with reference to Fig. 1.

When it is desired to open the container of Fig. 2, the outer end 6^a of retaining wire is pulled downwardly, which results not only in straightening the crimped edge of the closure cap but also in exposing the outer end of the sealing string 4^a so that after the wire has been removed the exposed end of the gasket may be grasped and likewise removed from between the container and cap skirt. Thus, because the inner end of the retaining wire pulls outwardly and exposes below the skirt the outer end of the gasket, the retaining wire is in its seal breaking effect a continuation of the string-like gasket. The removal of the retaining wire and gasket completely breaks the vacuum and leaves the cap simply lying on the top of the container.

The invention is applicable to closing or sealing bottles or similar containers having mouths which are narrower than their body portions, as well as to wide mouthed containers of the form shown in Figs. 1 and 2. In Fig. 3 a seal of the form illustrated in Fig. 1 is shown as closing a bottle 9. To form a wedge-shaped annular space between the container and cap skirt, the outer wall of the

mouth of the container may be cylindrical and the cap skirt flared outwardly, as indicated in the bottle shown in Fig. 3. The neck of the bottle may be provided ⁵ interiorly with a ledge 10 for supporting a cover 11 which may be used as a temporary closure for the bottle while its contents is being consumed. In place of the cover 11 of Fig. 3, the bottle may be provided with a reclosing cork 12 as illustrated in Fig. 4. Manifestly other forms of containers may be sealed by the improved closure.

Various materials may be used as gaskets depending, among other things, on the material packed in the container. The gaskets, whether they are in the form of continuous rings as in the seal of Fig. 1, or are string-like as in the seal of Fig. 2, may be of vulcanized or unvulcanized rubber, flexible and compressible paper, waxed twine, or any other materials suitable for the purpose. As to the retaining wire, it may be formed of various bendable relatively soft metals, although aluminum has been found to be particularly suitable. In all forms of the closure the gasket makes a hermetic seal, while the retaining wire, wedged in below the gasket, not only compresses the gasket tightly into position, but also firmly holds the cap upon a container and gives mechanical strength to the closure to resist the various forces which tend to dislodge the gasket.

An important advantage of seals of this character is that there is required no bead or other special finish on the outer walls of container mouths to render seal tight and durable, and therefore tumblers suitable for subsequent use as drinking glasses may be used as containers. Furthermore, when the seal is broken and the cap removed, the cap, being unbroken by its removal, may be used as a reclosure for the container while its contents are being consumed.

The placing of the gasket and retaining wire in the annular space formed between the container and cap skirt may be accomplished by a single machine provided with a small roller or equivalent device for engaging and forcing upwardly the sealing and retaining member, or other suitable mechanism may be provided for this purpose. A machine well adapted for making the closure is the subject matter of a separate patent application.

I claim:

1. The combination with a container, of a metal cap closing the mouth of the container and having a depending skirt forming with the wall of the container an annular space, a sealing gasket in the top of said space, and a wire in said space against the lower edge of the gasket and retaining the cap firmly upon the container.
2. The combination with a container, of a

metal cap closing the mouth of the container and having a depending skirt forming an annular space with the wall of the container, a sealing gasket in the top of said space, and a retaining wire in said space ⁷⁰ below the gasket and pressing upwardly against the gasket and outwardly against the cap skirt and thereby holding the cap firmly upon the container.

3. The combination with a container, of a metal cap having a depending skirt forming an annular space with the outer wall of the container, a sealing gasket in the upper portion of said space, and a retaining wire ⁸⁰ in said space against the lower edge of the gasket, the retaining wire being engaged and held in place by the cap skirt and in turn holding the cap upon the container.

4. The combination with a container, of a metal cap having a depending skirt forming with the outer wall of the container an annular space, a sealing gasket in the top of said space, and a retaining wire in said space against the lower edge of the gasket and engaged by the cap skirt, said wire ⁹⁰ holding the cap upon the container, and the outer end of the wire protruding below the lower edge of the cap skirt for engagement to remove the wire.

5. The combination with a container, of a metal cap having a depending skirt forming an annular space with the wall of the container, a sealing gasket in the top of said space, and a retaining wire in said space against the gasket and holding the cap upon the container, the lower edge of said skirt being crimped inwardly below the retaining wire, and the outer end of the retaining wire protruding below the lower crimped edge of the skirt for engagement ¹⁰⁰ to remove the wire.

6. The combination with a container, of a metal cap having a depending skirt forming with the outer wall of the container an annular space of wedge-shaped cross section with its base downward, a sealing gasket in the top of said space, and a retaining wire in said space against the lower edge of the gasket, the retaining wire being engaged and held in place by the cap skirt and in turn holding the cap upon the container.

7. The combination of a container having an outwardly flaring wall at its mouth, a cap closing the mouth of the container and having a depending substantially cylindrical skirt forming with the outer wall of the container mouth an annular space of wedge-shaped cross section, a sealing gasket in the top of said space, and a wire in said space against the lower edge of the gasket retaining the cap upon the container.

8. The combination of a tumbler having a smooth outwardly flaring wall at its mouth, a cap closing the mouth of the

tumbler and having a depending substantially cylindrical skirt forming with the outer wall of the tumbler an annular space of wedge-shaped cross section, a string-like sealing gasket wound around the mouth of the container in the top of said space, and a wire wound around the tumbler in said space against the lower edge of the gasket retaining the cap upon the container, the lower edge of the skirt being crimped inwardly, and the outer end of the wire protruding below the crimped edge of the skirt.

9. The combination with a container, of a metal cap having a skirt forming with the container an annular space of wedge-shaped cross section, and a string-like sealing and cap-retaining member wound in said space and having its outer end protruding from between the container and skirt for engagement to unwind the member and thereby release the cap.

10. The combination with a container, of a metal cap having a skirt forming with the container an annular space of wedge-shaped cross section, and a string-like sealing and cap-retaining member wound in said space and having its outer end protruding from between the container and skirt for engagement to unwind the member and thereby release the cap, said member consisting of a compressible gasket in the inner and a retaining wire in the outer portion of said space.

11. The combination with a container, of a metal cap having a depending skirt forming with the container an annular space of wedge-shaped cross section, and a string-like sealing and cap-retaining member wound in said space, the lower edge of said skirt being crimped inwardly below the sealing member, and the outer end of the sealing member protruding below the skirt for engagement to unwind the member and thereby bend the skirt outwardly and release the cap.

12. The combination with a container, of a metal cap having a depending skirt forming with the container an annular space of wedge-shaped cross section with its base downward, and a string-like sealing and cap-retaining member wound in said space and consisting of a flexible gasket in the inner and a retaining wire in the outer portion of said space, the lower edge of said skirt being crimped inwardly below said retaining wire, and the outer end of the retaining wire protruding below the skirt for engagement to unwind the retaining wire and thereby bend the skirt outwardly and release the cap.

13. The combination with a container, of a metal cap having a skirt forming an annular space with the outer wall of the container, and a string-like gasket wound in the upper and a retaining wire in the lower

portion of said space, the outer end of the gasket overlapping the outside of the inner end of the wire, and the outer end of the wire protruding below the skirt for engagement to release the cap, whereby the removal of the retaining wire causes the outer end of the gasket to be exposed below the skirt.

14. The combination with a container, of a metal cap having a skirt forming with the container an annular space of wedge-shaped cross section, and a string-like flexible and compressible gasket wound in the upper and a retaining wire in the lower portion of said space, the outer end of the gasket overlapping the outside of the inner end of the wire, and the outer end of the wire protruding below the skirt for engagement to release the cap, whereby the removal of the retaining wire causes the outer end of the gasket to be exposed below the skirt.

15. The combination with a container, of a cap formed of resilient metal closing the mouth of the container and forming an annular space with the wall of the container, a sealing gasket in the top of said space, and a retaining wire in the space below the gasket, said retaining wire pressing upwardly against the gasket to hold it in position and outwardly against the cap skirt placing it under tension and holding the cap upon the container.

16. The combination with a container, of a cap formed of resilient metal closing the mouth of the container and forming with the outer wall thereof an annular space of wedge-shaped cross section, a sealing gasket in the top of said space, and a retaining wire in said space below the gasket, said retaining wire pressing upwardly against the gasket to hold it in position and outwardly against the cap skirt placing it under initial tension and holding the cap upon the container.

17. The combination with a container, of a cap formed of resilient metal closing the mouth of the container and forming with the outer wall thereof an annular space of wedge-shaped cross section, a string-like sealing member wound in the top of said space, and a retaining wire in said space below the gasket, said retaining wire pressing upwardly against the gasket to hold it in sealing position and outwardly against the cap skirt placing it under tension and holding the cap upon the container, the lower end of said wire protruding below the cap skirt.

18. The combination with a container, of a cap formed of resilient metal closing the mouth of the container and forming with the outer wall thereof an annular space of wedge-shaped cross section, a string-like flexible and compressible gasket wound in the top of said space, and a retaining wire wound in said space below the gasket and

having its outer end protruding below the cap skirt, said retaining wire pressing upwardly against the gasket to hold it in position and outwardly against the cap skirt placing it under tension, the outer end of the gasket overlapping the outside of the inner end of the wire whereby the removal

of the retaining wire causes the outer end of the gasket to be exposed below the skirt.

In testimony whereof, I sign my name. 10
DALE M. BOOTHMAN.
